UNITED STATES PATENT OFFICE.

ULRICH STEINER, OF WAYNESBORO, PENNSYLVANIA, ASSIGNOR TO LANDIS TOOL COMPANY, OF WAYNESBORO, PENNSYLVANIA, A CORPORATION.

GRINDING-MACHINE.

1,078,563.

Specification of Letters Patent.

Patented Nov. 11, 1913.

Application filed July 26, 1912. Serial No. 711,701.

To all whom it may concern:

Be it known that I, ULRICH STEINER, a citizen of the United States, residing at Waynesboro, Franklin county, and State of Pennsylvania, have invented and discovered 5 certain new and useful Improvements in Grinding-Machines, of which the following is a specification.

My said invention consists in various improvements in the details of construction and arrangement of parts of mechanism for feeding the grinding wheel of grinding machines to the work, and regulating and controlling said feed, whereby certain advantages are secured contributing to greater proficiency and accuracy in the operation and result, all as will be hereinafter more fully described and claimed.

Referring to the accompanying drawings 20 which are made a part hereof, and on which similar reference characters indicate similar parts, Figure 1 is a front elevation of a portion of a grinding machine embodying my said invention, the general construction 25 of the machine being of the well known "Landis" type to which this invention particularly relates, Fig. 2 a side elevation of the transversely movable grinding wheel base and the slide by which it is mounted 30 on the longitudinal movable carriage, Fig. 3 a sectional elevation of the automatic feed mechanisms for the grinding wheel, Fig. 4 a sectional plan view of the same on the dotted line 4—4 in Fig. 3, Fig. 5 a vertical 35 sectional view on the dotted line 5—5 in Fig. 4, Fig. 6 a sectional view on the dotted line 6—6 in Fig. 5, Fig. 7 a detail perspective view of the feed regulating plate, Fig. 8 a detail sectional view through a portion 40 of the grinding machine illustrating the means for operating the weighted plunger, Fig. 9 a detail sectional view on the dotted line 9—9 in Fig. 8, Fig. 10 a vertical sectional view through the beveled gear and 45 the adjacent parts, Fig. 11 a face view of the cam ring, and Figs. 12 and 13 detail views illustrating parts referred to, more clearly.

In said drawings the portions marked A 50 represent the bed or casing, B the grinding wheel carriage, and C the grinding wheel base, all of which parts are in general of the well known Landis type.

Referring in detail to the drawings, 1 55 designates a drum mounted upon a shaft 2

within the casing A of the grinding machine. A belt 3 passes over said drum and drives a pulley 4 on the grinding wheel spindle for imparting motion to the grinding wheel 5. The belt 3 passes over a tensioning pulley 6 and an idler 7, the tensioning pulley 6 being mounted in any suitable manner. In addition to these pulleys described the belt 3 also passes over a pulley 8 mounted upon a shaft 9 for the purpose of operating the rapid feed mechanisms. A sleeve 10 is slidably mounted upon said shaft 9, said sleeve having secured thereto friction cones 11 and 12, the said cone 11 being provided with a sleeve 13 having therein a groove 14. A ring 15 is loosely mounted within the groove 14 said ring being secured to a yoke 16 by means of pivot bolts 17. The yoke 16 is pivotally mounted at 18 on an arm 19 formed on a bearing 20 in which bearing one end of the shaft 9 is mounted. The yoke 16 is provided with a right angular arm 21 pivoted at 22 to a lever 23 which extends through the casing A and is pivoted to the lower end of a lever 24 within convenient reach of the operator. A friction disk 25 mounted upon a shaft 26 is adapted to engage either one of the cones 11 or 12 when said cones are brought into position by manipulation of the lever 24. The shaft 26 is mounted in a bearing 27 and has secured thereon a beveled pinion 28 which meshes with a pinion 29 secured to a shaft 30 mounted within the tubular bearing 31 extending upward from the casing A on the carriage. Another pinion 32 is mounted on the lever end of shaft 30 below pinion 29 which meshes with a beveled gear 33 mounted upon a horizontal shaft 34, which is mounted in a suitable bearing 35. Said shaft has a beveled pinion 36 secured thereto which meshes with a beveled pinion 37 on one end of a screw-shaft 38, which is secured in a bearing 39 on the longitudinally movable carriage B. 100

The base C is mounted to traverse across the longitudinally movable carriage B in the usual manner and carries the grinding wheel 5. A nut 40 is carried by said base and the threaded portion of the shaft 38 passes 105 through said nut and imparts motion to the base C in either direction through the operation of the friction and beveled gears previously described. It is obvious from the foregoing description that the direction of 110

rotation of the shaft 38 and consequently the direction of travel of the base C is determined by the contact of disk 25 with either of the cones 11 or 12.

5 Rigidly mounted upon the shaft 30 is a ring 41, the said ring having a hub 42 for engagement with the said shaft, and also having rigidly secured upon its periphery a ratchet ring 43. The teeth of this latter ring 10 are adapted to be engaged by a pawl 44 mounted upon a stud 45 secured in an arm 46. This arm is formed upon a sleeve 47 rotatably mounted upon the shaft 30 immediately below the ring 41, the pawl 44 engaging the teeth of the ring 43 and imparting movement thereto when the arm 46 is moved in the direction of the arrow shown in Fig. 6 of the drawing. The pawl 44 is held into engagement with the teeth of the 15 ratchet 43 by means of a spring 48. The sleeve 47 is formed with a plurality of beveled teeth 49 for engagement with similar teeth 50 formed upon the upper end of one arm 51 of an L-shaped lever. This lever is 20 pivoted at 52 to the tubular bearing 31 and its opposite arm 53 is formed with a segmental gear 54. The teeth of this gear are adapted to engage a rack 55 formed upon a sleeve 56, secured by a set-screw 57 to a vertically 25 movable plunger 58. The plunger 58 is mounted to slide vertically within a sleeve 59 mounted within the casing A, and is held, in its lowermost position by means of a weight 61 mounted thereon. The lower end 30 of this plunger 58 has secured thereto a roller 62 which rests upon an arm 63 rigidly secured to a shaft 64 mounted in suitable bearings within the carriage. Said shaft 64 has secured thereto a radial blade 35 65, the said shaft and blade extending the full length of the carriage B so that the blade will at all times engage roller 66 mounted on a pivot carried by a collar 67 upon a horizontally movable rod 68. The 40 rod 68 is mounted in a bearing 69 in the machine casing A and is operated by means of a cam 70, the said cam being formed upon a ring 71. This ring 71 is mounted upon a horizontal rim 72 of a beveled gear 73, the 45 said gear being mounted upon shaft 74 and receiving motion from the pinion 75 mounted upon a shaft connected with the driving mechanism of the longitudinally movable carriage B. The ring 71 carrying the cam 70 is mounted to normally slip upon the rim 72 of the gear 73, as will be presently described, and is adapted to be fixedly secured to the said gear through the medium of a notched ring 76 fastened to the gear 73 by 50 means of pins 77. The connection between the ring 71 and the ring 76 is made through the medium of a plunger 78, having a tooth or point 79 which is held in engagement with the ring 76 by means of a spring 80.

55 It is thus apparent that when these parts

are in their engaged position the ring 71 will move with the gear 73, operating the cam 70 of the said ring and causing the reciprocation of the rod 68, which rod bears against the blade 65 and raises the plunger 58, which 70 operates the arm 51 and rotates the sleeve 47. In order that the ring 71 may be released from the gear 73 after the plunger 58 has completed a movement, said plunger 78 carries at its top a roller 81, the said roller being adapted for engagement with either one 75 of a pair of lifting pawls 82. These pawls are formed upon the ends of rods 83 suitably secured as at 84 in the casing A of the machine, and held in proper spaced relation 80 at their ends by a spacing bar 85. This bar, in addition to holding the cams properly spaced apart, lends rigidity to the outer ends of the bars 83 and prevents movement when the roller 81 comes in contact with either 85 pawl 82. When this takes place the tooth 79 of the plunger 78 is lifted from engagement with the notched bar 76 and releases the ring 71 from the gear 73.

By referring to Fig. 11 it will be noted 90 that one side of ring 71 is formed with two free segmental flanges 150 connected by a clamping screw 151 by which said ring may be held to gear 73 by friction sufficient to cause said ring to move back with said gear 95 when it reverses and free rollers 81 from dogs 82 permitting point 79 of plunger 78 to engage the notches of ring 76 and lock the parts positively together until the other dog 82 engages roller 81 and releases said engagement. Said flanges 150 may be lined with 100 leather or other frictional material as found desirable. A spring 152 is preferably interposed under the head of clamping screw 151 to maintain its tension as required.

105 Loosely mounted upon the ratchet ring 43 is a ring 86, the said ring having mounted thereon an adjusting worm 87 for engagement with a worm gear 88 formed upon the ring 41 to which the ratchet ring is secured. The worm 87 is pivotally mounted as at 89 upon the ring 86 so that it may be swung into and out of engagement with worm wheel 88 as desired. Said worm 87 is normally held in engagement with wheel 88 by 110 a spring 153, which spring is secured on the top surface of ring 86 and bears outwardly against the periphery of a knob 154 on the handle end of said worm, (see Fig. 13). Said knob is formed with four notches in 115 its periphery equi-distant, or 90°, apart, and said spring is bent in its upright portion to form a point 155 to engage said notches, for a purpose to be presently described.

120 The ring 86 just described has secured thereto by means of screws 90 an interference plate 91, (Figs. 6 and 12), the said plate being for the purpose of covering certain of the teeth of the ratchet ring 43 so that only a portion of the said teeth may be 125 130

exposed for engagement with the pawl 44. Worm 87 seems to adjust said ring 86 and said interference plate 91 carried thereby, to determine the point for stopping the feed. Said worm is designed so that one complete turn will move plate 91 over the toothed edge of ring 43 a distance to vary the feed of the grinding wheel to the work one-thousandth of an inch and it follows that by giving said work one-quarter of a turn, or sufficient to carry point 155 of spring 153 from one notch to the next in periphery of knob 154 the feed will be varied one-quarter of a thousandth of an inch. A handle 156 is provided on ring 86 by which it may be turned by hand when worm 87 is disengaged. This may be accomplished by swinging it outwardly on its pivot, knob 154 being swung inwardly against spring 153. This spring 153 not only serves to hold worm 87 normally in operative engagement with wheel 88, but acts as a gage to determine the extent of its movement. At the same time said worm may be readily held out of engagement while the feed regulating means is moved to approximate position by hand.

The tubular bearing 31 of the shaft 30 is provided with a projecting arm 92, which carries a pair of upright members 93 having a feed regulating plate 94 mounted on the upper ends thereof. This plate is provided with a vertical member 95, also adapted to cover a portion of the teeth of the ratchet 43 and arranged to work over the outside of the interference plate 91. Said plate may be adjusted to and fixed in any desired position through the medium of clamping bolt 96 extending through a segmental slot therein, which position or adjustment may be determined by scale 103 of plate 94 and a pointer 156 carried on adjacent upright member 93. The member 95 of said feed regulating plate 94 is positioned to determine the forward feed of the grinding wheel, and consequently the amount of material to be removed from the work at each traverse of the carriage B, while the interference plate 91 is for the purpose of stopping said feed at a predetermined point as when the work has been ground to its exact finished size. A knock-out dog 97 is mounted upon a stud 98 on one of the upstanding members 93 and is adapted for contact with a pin 99 secured upon the under side of the pawl 44, the engagement of this pin with the beveled end 100 of the dog 97 prevents the engagement of the pawl 44 with the teeth of the ratchet ring 43.

For the purpose of determining the amount of feed of the grinding wheel at each reversal of the carriage C suitable graduations 103 are provided upon the feed plate 94, and graduations 102 are provided upon the edge of ring 41 for setting the worm 87. Extending from the sleeve 31 is

an arm 106 carrying a stop 107 adapted to engage a dog 111 movably secured in a groove 112 in the underside of the ring 41. A set screw 157 is provided for securing dog 111 in adjusted position. The arm 106 also carries a pointer 109 while another pointer 110 is carried by said dog 111. Said pointer 109 is stationary and is used to determine the distance from which pointer 110 may be set. Dog 97 serves to throw pawl 44 out of operation at a fixed point regardless of the length of the stroke of arm 46 carrying it, which variation is caused by variation in the torsional strain on shaft 64 at different positions, for, as will be seen, when the plunger 58 is opposite the rod 68 the torsion will be slight and consequently the pawl 44 will be moved farther than when the carriage is at its extreme position and shaft 64 under more or less torsion or twist. Said dog 97 extracts the pawl before it reaches its extreme forward movement and thus a uniformity of action is maintained in all positions of the parts.

The operation is as follows: The power being applied to the machine, shaft 8 is driven, as before described. By the manipulation of lever 24 the grinding wheel carriage may then be fed rapidly toward, or from, the work as desired, by the mechanism before described. After the grinding wheel is approximately in contact with the work the power feed is thrown out of gear and it is fed up to operative position through the medium of the hand wheel 101. The automatic mechanism is then set for operation. Regulating plate 94 is adjusted so that the front end of its upright member 95 will permit the length of engagement between pawl 44 and the teeth or ring 43 to secure the length of stroke, or degree of rotation, to said wheel 43 desired to obtain the desired feed into the work. Ring 86 is then turned to bring interference plate 91 to the position to throw said pawl out of operation when the work has been ground to the predetermined size. Near the completion of the work if the operator finds that further reduction in the size of the work should be made he is enabled, by turning the worm 87, to turn back ring 86 just the distance necessary to permit the further forward feed of the grinding wheel into the work required to secure the exact finished size desired. A one-quarter turn of the worm secures a one-quarter of a thousandth of an inch reduction in the size of the work, and other fine adjustments can be secured in the same manner. These various adjustments are readily determined through the medium of the indicators and scales provided with various parts as before described. Thus as the carriage traverses back and forth and the cam 70 is oscillated rod 68 operates, rock shaft 64 and reciprocates

plunger 58 carrying rack 55, which through the engagement with the rack 54 and the angle lever composed of the arms 51 and 53, operates the sleeve 47 and through it 5 pawl 44 to turn ring 41, which turns shaft 30 and through said shaft feeds the grinding wheel to the work.

The mechanism shown particularly in Figs. 9, 10, and 11 provides for the positive 10 operation of plunger 58 or permits said plunger to stand idle after a completion of one movement until the carriage reverses, this result being secured through the medium of the normal frictional engagement 15 between ring 71 and gear 72 and the positive lock engagement during the period of the movement between dogs 82, which movement is regulated to provide for one complete movement of said plunger.

20 It will thus be seen that the traverse of the carriage can be regulated to suit the work and the feed of the grinding wheel regulated to automatically reduce it to a predetermined size, and that the grinding wheel can be moved rapidly toward and from the work by power, thus providing a machine of a very accurate and efficient character and one that is conveniently and easily operated.

25 Having thus fully described my said invention what I claim as new and desire to secure by Letters Patent is:

30 1. In a grinding machine the combination of a frame, work supporting mechanism, a grinding wheel carriage, operating mechanism for said parts, a grinding wheel mounted upon said grinding wheel carriage, and means for automatically feeding the grinding wheel to the work comprising 35 gearing operated by the reversal of the carriage, means for regulating the amount of feed at each reversal, means for limiting the feed at a predetermined point to secure the size of finished work desired, and means for 40 varying the position of said limiting means embodying a worm connection the worm whereof is pivoted and adapted to be swung out of said connection when desired, substantially as set forth.

45 2. In a grinding machine the combination of work holding mechanism, grinding mechanism, means for automatically feeding the grinding wheel to the work operated by the carriage operating mechanism at each reversal of the carriage to feed the grinding wheel a predetermined distance, means for 50 rendering said feed mechanism inactive at a predetermined point, and means for varying and determining the limit of feed embodying a worm wheel adjustment, said worm being mounted on a pivot and normally held in engagement by a spring which 55 spring also serves as an indicator to determine the amount of adjustment, substantially as set forth.

3. In a grinding machine an automatic feed mechanism for the grinding wheel comprising means for limiting the feed at a predetermined point which includes adjusting mechanism for varying said point, said adjusting mechanism comprising a worm wheel and an adjusting worm engaging therewith, said worm formed with engaging notches in its periphery spaced apart to determine certain degrees of adjustment,

70

and a spring arranged to normally hold said worm in engagement with said worm wheel and formed to engage said notches, substantially as set forth.

75

4. In a grinding machine an automatic feed mechanism for the grinding wheel connected to be operated from the carriage operating mechanism, an operating shaft, a circular ratchet on said operating shaft,

80

a reciprocating pawl for operating said ratchet step by step, an interference plate mounted to be adjusted on said circular ratchet and adapted to cover a portion of the teeth thereof, means for adjusting said interference plate to limit the operation of

85

said pawl, said adjusting means including a worm mounted on said interference plate and engaging with a worm wheel formed on said ratchet, said worm being mounted on a pivot and formed with notches in its periphery, and a spring mounted alongside the handle of said worm and arranged to normally hold the same in engagement and formed with a point for engaging said notches, substantially as set forth.

90

5. In a grinding machine an automatic feed mechanism for the grinding wheel comprising an operating shaft geared to feed said grinding wheel to and from the work, a circular ratchet on said operating shaft, a reciprocating plunger adapted to be operated at each reversal of the carriage, a pivoted angle lever having a segmental ratchet

95

on one end engaging with a ratchet carried by said plunger, and a segmental ratchet on its other end engaging with a ratchet on a sleeve, said sleeve mounted to oscillate on said operating shaft and having a radial arm extending adjacent to the edge of said circular ratchet, a pawl pivoted on said radial arm adapted to engage said circular ratchet, and a dog positioned adjacent to said pawl to throw the same out of engagement with said ratchet at a fixed point in its forward movement, substantially as set forth.

100

6. In a grinding machine an automatic feed mechanism for the grinding wheel comprising an operating shaft operatively geared to said feed mechanism, a circular ratchet on said operating shaft, an oscillating sleeve also mounted on said shaft having an arm extending to a point outside of said circular ratchet, a pawl pivoted to said arm, means for normally holding said pawl into

105

an engagement with said ratchet, and a dog positioned adjacent to said pawl to throw the same out of engagement with said ratchet at a fixed point in its forward movement, substantially as set forth.

110

engagement with said ratchet, a dog in a fixed position in the path of said pawl for disengaging it from said ratchet, and means for oscillating said sleeve at each reversal of the carriage, substantially as set forth.

7. An automatic feed mechanism for the grinding wheel of grinding machines comprising a operating shaft operatively geared to said feed mechanism, a circular ratchet fast on said operating shaft, an oscillating sleeve mounted loosely on said shaft, a pawl pivoted to an arm of said oscillating sleeve and adapted to engage said ratchet, a dog positioned to throw said pawl out of operative engagement at a fixed point in its forward movement, a gear on said sleeve, a reciprocating plunger, an operative connection between said reciprocating plunger and said gear on said sleeve, and means for reciprocating said plunger at each reversal of the carriage, substantially as set forth.

8. An automatic feed mechanism for the grinding wheel of grinding machines comprising an operative shaft operatively connected to said feed mechanism, a circular ratchet mounted thereon, an oscillating sleeve carrying a pawl for operating said ratchet step by step, a regulating plate mounted on supports adjacent to the edge of said ratchet, means for adjusting said plate to expose more or less teeth of said ratchet to the operation of said pawl, and means for reciprocating said pawl at each reversal of the carriage, substantially as set forth.

9. An automatic feed mechanism for the grinding wheel of grinding machines comprising an operating shaft operatively connected with said feed mechanism, a wheel on said operating shaft formed with ratchet teeth in its periphery, a reciprocating pawl alongside said periphery, and adapted to engage with said ratchet teeth, a regulating plate supported alongside said wheel with a member adapted to cover a portion of the periphery thereof, means for adjusting the position of said plate to expose more or less of said periphery to the operation of said pawl, another plate mounted to rotate with said wheel and carrying a member covering a portion of the periphery thereof, means for adjusting said plate toward or from the operative position of said pawl, means for determining the adjustment, and means for operating said pawl at each reversal of the carriage, substantially as set forth.

10. An automatic feed mechanism for the grinding wheel of grinding machines comprising an operating shaft operatively connected to said feed mechanism, gearing connected with said operating shaft for turning it step by step, a reciprocating plunger operatively connected to said means, a rock shaft extending from end to end of the grinding wheel carriage and carrying a

radial arm adapted to operate against the lower end of said plunger, a reciprocating rod adapted to operate against the other radial arm carried by said rock shaft, and means for operating said reciprocating rod at each reversal of the carriage, substantially as set forth.

11. An automatic feed mechanism for the grinding wheel of grinding machines comprising an operating shaft operatively connected to said feed mechanism, means for imparting intermittent motion to said operating shaft, a reciprocating plunger operatively connected to said means, a rock shaft provided with a radial arm for operating said plunger in one direction, a radial plate extending the length of said shaft, a reciprocating rod operating against said plate to rock said shaft, and an oscillating cam carried by the carriage reverse mechanism for reciprocating said rod, substantially as set forth.

12. An automatic feed mechanism for grinding wheels of grinding machines comprising an operating shaft operatively connected to said feed mechanism, a reciprocating plunger geared to said operating shaft to impart intermittent feed movement thereto, a rock shaft suitably supported, a radial arm on said rock shaft carrying the lower end of said plunger, a radial plate also carried by said rock shaft, a reciprocating rod operatively connected to said plate at one end and bearing against a cam formed on a cam ring at the other end, said cam ring normally mounted by frictional contact on a gear connected with the carriage feed mechanism, means for coupling said cam ring positively to said gear for a period in its movement, and means for disengaging said positive coupling at the end of said period, substantially as set forth.

13. An automatic feed mechanism for grinding wheel of grinding machines comprising an operating shaft operatively connected with said feed mechanism, a reciprocating plunger connected to impart intermittent feed motion to said operating shaft, a weight for operating said reciprocating plunger in one direction, a rock shaft, a radial arm on said rock shaft operatively supporting the lower end of said plunger, a radial plate extending from said rock shaft, a reciprocating rod operatively connecting with said plate at one end and bearing at its opposite end on a cam slidably connected to a gear, a pawl for positively connecting said cam to said gear during a part of its movement, and dogs positioned to withdraw said pawl from engagement at the respective limits of said movement, substantially as set forth.

14. A feed mechanism for the grinding base of grinding machines comprising an operating shaft, a gear connection running

from said operating shaft to means for sliding said base back and forth, another gear connection running from said operating shaft to a power shaft, said last-named gear connection embodying a clutch adapted to be thrown into mesh for operating said shaft in either direction, substantially as set forth.

15. A feed mechanism for the grinding wheel base of grinding machines comprising an operating shaft, a screw carried on the carriage and engaging with a nut on the base, a driving connection between said screw and said operating shaft, a power

shaft carried by said grinding wheel carriage, and gear connecting said power shaft and said operating shaft which embodies a clutch adapted to couple said shaft to said power shaft for operation in either direction, substantially as set forth. 15

20 In witness whereof, I have hereunto set my hand and seal at Washington, District of Columbia, this 23rd day of July, A. D. nineteen hundred and twelve.
